UNITED STATES PATENT OFFICE.

ROLAND D. PARRISH, OF RICHMOND, VIRGINIA.

DESIGN FOR A MOTOR-VEHICLE FRONT ASSEMBLY.

Application filed February 19, 1929. Serial No. 30,132. Term of patent 14 years.

To all whom it may concern:

Be it known that I, ROLAND D. PARRISH, a citizen of the United States, residing at Richmond, in the county of Henrico and State of Virginia, have invented a new, original, and ornamental Design for a Motor-Vehicle Front Assembly, of which the following is a specification, reference being had to the accompanying drawing, forming part thereof.

Figure 1 is an elevational view of the front end of a motor vehicle front assembly embodying my design;

Figure 2 is a view in top plan of the motor vehicle front assembly embodying the design.

I claim:—

The ornamental design for a motor vehicle front assembly, as shown.

ROLAND D. PARRISH.
